TIME-OPERATED COIN-CONTROLLED
SIGNAL APPARATUS

Charles H. Martin, West Springfield, Mass.

Application February 13, 1937, Serial No. 125,600

3 Claims. (Cl. 161—15)

This invention relates to improvements in time-operated coin-controlled signal apparatus and is directed more particularly to apparatus known as parking meters.

5 The apparatus of the invention is characterized by a signal which is shiftable between signal and non-signaling locations or positions by means of a timing mechanism that is under the control of a coin-controlled mechanism. In its 10 broad aspects, where the novel features of the invention are used in connection with a parking meter, the operator of a vehicle has but to deposit a coin in the coin slot of the apparatus and operate a lever or knob whereupon the time 15 mechanism is wound and set in operation to locate a signal in one position; at the expiration of a predetermined period of time the timing mechanism shifts the signal to another position. As a special feature, in one of these positions, 20 the signal is visible so that it may be readily known whether the vehicle is rightfully parked.

It will be understood that while the novel features of the invention will be described in connection with a parking meter they are adapted 25 for use in apparatus constructed and arranged for other purposes as well.

According to one feature of the invention the apparatus includes a timing mechanism for operating the signal which is characterized by 30 means to automatically stop the operation of the timing mechanism at the termination of a predetermined period of time.

According to another feature of the invention the apparatus includes a time mechanism which 35 is set in operation to operate a signal by means of a coin mechanism which simultaneously functions to wind the timing mechanism and to set the timing mechanism in operation.

According to a further feature of the invention 40 the coin mechanism of the apparatus is provided with means to visibly display the coin on which the apparatus is operating. This makes it possible to immediately detect the presence of an unauthorized coin in the apparatus.

45 Various other novel features and advantages of the invention will be hereinafter more fully referred to in connection with the accompanying drawings wherein:

Fig. 1 is a small scale elevational view of the 50 apparatus of the invention;

Fig. 2 is an enlarged front elevational view of one of the interior plates of the invention to explain the time mechanism;

Fig. 3 is a fragmentary elevational view of cer- 55 tain parts of the time mechanism;

Fig. 4 is a longitudinal elevational sectional view on the line 4—4 of Fig. 1;

Fig. 5 is a rear elevational view of the coin-control mechanism;

Fig. 6 is a perspective enlarged fragmentary view of certain parts of the mechanism;

Fig. 7 is a perspective fragmentary view to explain certain features of the invention; and

Fig. 8 is a plan view to explain certain modifications which may be applied to the mechanism. 10

Referring now to the drawings more in detail, the invention will be fully described.

In a broad way the apparatus consists of a housing 2 which may be supported in any suitable manner as by a support 4. The housing 2 15 is hollow and at its forward side there is a coin mechanism 6, below which there may be a coin drawer 8 slideable in and out.

At 10 is indicated a slot to receive the coins which pass through the coin mechanism and 12 20 is a window to expose a coin which has passed through the coin mechanism and on which the apparatus is operated. There is a signal 14 which is movable up and down between an upper signaling position, wherein it is visible through a 25 dome 16, which may be of transparent material such as glass, and a non-signaling non-visible position.

As will hereinafter appear, the apparatus is 30 constructed and arranged so that when the parking meter is set alongside of a parking space an operator drops a coin in the slot 10 and operates an operating member 18, the coin passes down through the mechanism to lie behind the window 12. As the handle 18 is rotated the time 35 mechanism is wound and started in operation and the signal 14 disappears.

At the expiration of a certain predetermined period of time, according to the setting of the timing mechanism, the signal is elevated to signaling position in the transparent dome. This indicates that the parking time allowed by the coin and measured by the time mechanism has expired so that the signal then is, of course, an indication that the time for which the operator 45 has paid has expired.

In the housing there is a central plate 20 which carries on its rear side a time mechanism which may be enclosed by a casing 22 (see Fig. 4). A rotatable shaft 24 extends rearwardly from the 50 coin mechanism 6 and this is rotated as the handle 18 of the coin mechanism is rotated. This shaft 24 is utilized in the operation of the time and signal mechanism as will be hereinafter described. 55

The signal 14 as shown in Fig. 2 is shiftable as by being freely slideable up and down on a guide rod 30 associated with plate 20. It is in signalling position in Fig. 2 and is held therein by a signal shifting lever 32 pivoted at 34 to plate 22. The time mechanism may be of any well-known form but in the form of the invention shown it includes a gear 36 which is actuated by spring means to be described.

10 This gear 36 meshes with and drives a gear 38 on a shaft 40. A gear 42 on shaft 40 meshes with a gear 44 on shaft 46 and another gear 48 on said shaft 46 meshes with a gear 52 on a shaft 50. Another gear 54 on shaft 50 meshes with a gear 56 which gear is associated with an escapement ratchet wheel 58.

An escapement lever 60 pivoted at 62 has prongs or pawls 60' which co-operate with the ratchet, and a balance wheel 66 and hair spring 20 (not shown) is provided as is usual in mechanisms of this kind. The parts described are suitably journaled between plate 22 and a plate 71 secured thereto by posts 72 and 73.

25 A spring 68 has one end secured to a shaft 70 and its other end is secured to the post 72. A ratchet wheel 74 (see Fig. 3) is also secured to shaft 70 while a pawl 76 is pivoted to gear 36 so as to engage the teeth of ratchet 74. A spring member 78 acts on the ratchet 76 so that the shaft 70 and ratchet wheel 74 may rotate relative to gear 36 in one direction while the ratchet 76 drives the gear 36 in the opposite direction.

30 As shaft 70 is rotated counterclockwise with reference to Fig. 2, or clockwise with reference to Fig. 3, the spring 68 is wound up to store energy in the spring, the ratchet 74 rotating with the shaft passes by the pawl 76. When the escapement lever 60 oscillates up and down the spring mechanism of course operates the time mechanism and shaft 70 is rotated counterclockwise 40 in Fig. 2. When the escapement lever 60 is stopped in its oscillation the time mechanism is rendered inoperative.

45 In the operation the shaft 70 which may be rotated counterclockwise to wind the spring becomes the operating shaft or driver like the shaft for the hands of a clock, when the escapement mechanism operates, since it is rotated clockwise by the spring as long as the escapement operates.

50 A lever 80 rotatable with shaft 70 carries a pin 82 which is engageable with a cam part 84 of the signal lever 32, while a lever 86 which carries a pin 88 is also rotatable with shaft 70. A lever 90 swingable on a pivot 92 carries a pin 94. A stop member 96 in the form of a rod extending from lever 90 is arranged to act on escapement lever 60, to stop and start the escapement.

55 The rotatable shaft 24 of the coin mechanism 6 carries a cam member 26. In Fig. 2 the parts are shown with the signal in signaling position with the time mechanism inoperative. When cam 26 is rotated clockwise by shaft 24 the cam acts on pin 94 of lever 90 and on pin 88 of lever 86. The lever 90 is moved clockwise and lever 86 is moved counterclockwise.

60 As lever 86 swings counterclockwise it rotates shaft 70 to wind up the spring 68 while lever 80 at the same time releases lever 32 so the signal 70 assumes its non-signaling position. As lever 90 moves clockwise the member 96 acts on the escapement lever 60 to start the time mechanism. As the time mechanism operates, the shaft 70 rotates clockwise so that lever 80 swings upwardly whereby the pin thereof engages cam 84

of lever 32 to raise said lever 32 upwardly and elevate the signal 14 to signaling position.

65 A rod 100 has its upper end engaged with a projection 102 on lever 32 while its lower end is slideable in an eye 104 on lever 90. The lower extremity of the rod is preferably formed so that as lever 32 is elevated the rod causes lever 90 to be elevated whereby member 96 engages the escapement lever to stop the time mechanism.

70 Lever 80 and the lever 86 may be so arranged on the shaft 70 as to cause the time mechanism to operate for any desired predetermined length of time such as an hour, half-hour, three hours, or the like. The time mechanism will operate through a period of time depending on the angle 15 through which arm 80 swings from its lower to its upper inoperative position and of course this angle may be varied in various ways, all as may be desired.

75 According to one form of the invention as shown in Fig. 8 an arm such as 110 may be rotatable on shaft 70 and adjustably secured to a lever 112 which is fixed on said shaft. The said lever 110 may be secured to the lever 112 by means of a screw 114 which passes through a 25 slot 116 of lever 112, or in some other way.

80 The coin mechanism 6 may be of usual form such as shown in United States Letters Patent 1,850,382 of March 22, 1932, but is shown in a general way in Fig. 5. As has been previously stated, 30 an operating member 18 is secured to a rotatable shaft 24 thereof. As a coin is deposited in the coin slot 10 of the coin mechanism the shaft 24 is released for counterclockwise rotation by member 18. In its rotation levers 116 and 130 of the coin 35 mechanism (see Fig. 5) are moved clockwise by a cam 118 on shaft 24, and the coin, indicated by c, moves downwardly past levers 116 and 130 and comes to rest on a stop or stops 122. When at rest the coin c is disposed adjacent the window 40 12 of the coin mechanism so that it may be readily ascertained whether the apparatus is operating on an authorized coin.

45 A lever 130 is pivoted at 132 for swinging movements and has a lower flange portion 134 which is cut away at 136 so as to overlie the coin c, while a kicker 138 extends outwardly from the flange 134. A spring 140 secured at one end to a pin 142 is in engagement with a pin 144 and has its outer end in engagement with the lever 130 so as to urge the lever 130 counterclockwise to hold the end of the flange in engagement with an abutment 146.

50 A projection 131 on lever 130 is engaged by a projection 24' of shaft as said shaft 24 is rotated counterclockwise whereby lever 130 is swung clockwise. Thereby when a subsequent coin is deposited in the coin mechanism and the handle 18 is rotated to rotate shaft 24 the kicker 138 engages the coin c and moves it from behind the window. Thus every time the apparatus is operated the particular coin which is used to operate it is visible, while in the next operation that particular coin is removed so that the one on which the apparatus is operating is visible.

55 The back plate 71 of the time mechanism is preferably secured to the plate 20 by posts 72 and 73 while the coin mechanism may be secured to the plate 20 by one or more tie members such as 7.

60 While I have described the invention in great detail and with respect to a preferred form thereof, it is not desired to be limited thereto since many changes and modifications may be made 75

therein without departing from the spirit and scope of the invention. What it is desired to claim and secure by Letters Patent of the United States is:

- 5 1. A signal apparatus of the class described comprising in combination a support, a guide thereon, a signal on said guide movable up and down between upper and lower positions, a signal lever pivoted on said support for engaging and moving said signal upwardly, a time mechanism having a spring and a rotatable shaft for winding said spring when rotated in one direction and adapted to be rotated by said spring in an opposite direction, a lever associated with said shaft engageable with the signal lever when the shaft is rotated by the spring to actuate the signal for moving the signal upwardly, and means for rotating said shaft in said one direction.
- 10 2. A signal apparatus of the class described comprising in combination a support, a guide thereon, a signal on said guide, movable up and down between upper and lower positions, a signal lever pivoted on said support for engaging and moving said signal upwardly, a time mechanism having a spring and a rotatable shaft for wind-
- 15 ing said spring when rotated in one direction and adapted to be rotated by said spring in an opposite direction, a lever associated with said shaft engageable with the signal lever when the shaft is rotated by the spring to actuate the signal for moving the signal upwardly and retain the same in upper position, and means for rotating said shaft in said one direction.
- 20 3. A signal apparatus of the class described comprising in combination a support, a guide thereon, a signal on said guide movable up and down between upper and lower positions, a signal lever pivoted on said support for engaging and moving said signal upwardly, a time mechanism having a spring and a rotatable shaft for winding said spring when rotated in one direction and adapted to be rotated by said spring in an opposite direction, means for rotating said shaft in one direction, a member on said shaft, and a lever angularly adjustable on said member, all adapted and arranged whereby as said spring rotates the shaft the lever engages the signal lever to elevate the same and retain it in signal elevating position.

CHARLES H. MARTIN. 25
